(57) **CLAIM**

The ornamental design for the dual locking circuit board support, as shown.

DESCRIPTION

FIG. 1 is a front elevational view of a dual locking circuit board support embodying the present invention.

FIG. 2 is a rear elevational view of the dual locking circuit board support shown in FIG. 1.

FIG. 3 is a left side view of the dual locking circuit board support shown in FIG. 1.

FIG. 4 is a right side view of the dual locking circuit board support shown in FIG. 1.

FIG. 5 is a top view of the dual locking circuit board support shown in FIG. 1; and,

FIG. 6 is bottom view of the dual locking circuit board support shown in FIG. 1.
